UNITED STATES PATENT OFFICE.

DANIEL QUIGLEY TOWLES, OF YONGES ISLAND, SOUTH CAROLINA.

LOCK-HINGE.

1,210,234.

Specification of Letters Patent. Patented Dec. 26, 1916.

Application filed February 28, 1916. Serial No. 80,968.

To all whom it may concern:

Be it known that I, DANIEL Q. TOWLES, a citizen of the United States, residing at 5 Yonges Island, in the county of Colleton and State of South Carolina, have invented certain new and useful Improvements in Lock-Hinges; and I do hereby declare the following to be a full, clear, and exact description of the invention, such as will enable others skilled in the art to which it 10 pertains to make and use the same.

This invention relates to hinges, and more especially to those which lock, either positively or frictionally; and the object of the 15 same is to produce a hinge or pivot by means of which a pair of members may be connected with each other at various angles and perhaps locked in such position, and by means of which also the members may 20 be adjusted longitudinally of themselves along the leaves or elements of the pivot or hinge.

In the accompanying drawings I have shown this improved hinge or pivot as applied to the parts of a scaffold bracket as 25 for use in windows, but it will be obvious from the following specification that the invention is of much wider adaptability and therefore I should not be limited to this 30 use.

In the accompanying drawings—Figure 1 is a sectional view through a wall and window frame, showing a scaffold bracket mounted on the window sill and with its 35 parts connected by this improved hinge. Fig. 2 is an enlarged perspective view of the hinge itself and the members which it connects, and Fig. 3 is a still further enlarged sectional view on the line 3—3 of 40 Fig. 2. Figs. 4 and 5 are inner and outer views of one of the washer elements of this hinge; and Fig. 6 is a sectional detail showing the parts slightly separated and illustrating modifications or amplifications of 45 the idea.

I might say at starting that in the application of this invention to a scaffold bracket as seen in Fig. 1, the letter F designates a window frame let into a wall W, and H is 50 the horizontal bar or member of the scaffold bracket overlying the sill S of the window and held in such position by an oblique brace or member O and an upright member U. Scaffold brackets of this general type are old, but as far as I am aware 55 their members O and U need some means

for fastening them in the position shown. By the use of my improved hinge no such additional member or fastening means is necessary, because on tightening up the 60 hinge as explained below the members O and U will be held rigidly in the position shown in Fig. 1, and boards may be laid across the horizontal member H of the scaffold bracket from one window to another 65 or from one side of the sill to the other side as usual. On the above understanding, let us then assume throughout this case that we are using the improved hinge or pivot to connect two members H and O. In a 70 scaffold bracket there may be two horizontal members H, and these would be rigidly connected by a cross bar which does not appear in Fig. 1 but is shown in Figs. 2 and 3 and indicated by the letter C. In 75 the hinge alone, this cross bar is replaced by the head of the pintle or bolt as will be explained.

Coming now to the details of the invention, there are elements which may be called 80 washers if the device is considered as a pivot or leaves if the device is considered as a hinge. One of these we will call the male washer or leaf 1 and the other the female washer or leaf 11. The size and contour of 85 these elements or leaves are not important, but they may well be made round as shown, and they are pierced centrally with holes 2 and 12 which align when said elements are superimposed. Through these holes passes 90 the pintle of the hinge which is herein shown as a bolt 20 having a head 21 in Fig. 6, although the cross bar C takes the place of such head in Fig. 3. On the threaded end of this bolt screws a nut which may be 95 a thumb nut as shown at 22 or a plain nut as shown at 23. When this nut is set up tight it will be obvious that the contiguous faces of the two washers will be brought 100 into contact with each other, and the tighter the nut is set up the greater the friction generated by said contact. If it be desired that these elements shall not turn readily on each other, I provide their contiguous 105 faces with projections and protuberances about as seen in Fig. 3. If these are quite pronounced as designated by numerals 3 and 13, the nut may be set up sufficiently tight to absolutely lock the elements against rotation; but as shown in Fig. 6 these protuberances and depressions may be quite small—merely roughened in fact on the ad-

jacent faces as indicated at 4 and 14—and if so it is possible for the elements to turn one upon the other if the nut is not set up tight or if a spring is used under it as 5 described below. The outer faces of the washers 1 and 11 are also made irregular in order that the members H and O which this hinge is to connect may not slip on the washers. This irregularity may be effected 10 in a variety of ways, but in Fig. 3 it is shown as accomplished by cutting grooves or channels 5 and 15 diametrically across the outer faces of the washers 1 and 11. If two ordinary bars H and O are to be connected as seen in Fig. 1, these grooves will 15 be of a size to loosely receive said bars, and the latter will be longitudinally slotted as shown at 16 so that they will stand astride the bolt 20.

20 With this construction, the parts are assembled as best seen in Figs. 1 and 3. When now it becomes desirable to adjust the member O with respect to the member H, the nut 22 is loosened on the bolt 20 which first 25 frees the members O and H within the channels 5 and 15, and said members may therefore be adjusted longitudinally therein. A little further loosening of the nut 22 reduces the tension between the two 30 washers, so that the protuberances 3 may slip from one depression 13 to the next, and this permits the washers to be turned axially with respect to each other, when of course the members O and H are also swung 35 around the same axis. After the desired adjustment of parts has been effected, the nut is set up tight again as will be clear.

In Fig. 6 are shown several modifications or amplifications of which the idea is susceptible. I have made use of this view to 40 indicate that the projections or protuberances 4 and depressions 14 may not be so pronounced as shown in Fig. 3, and it will be understood that they may not be rounded 45 as shown so long as they are disposed around the central holes 2 and 12. In this view I have shown the element 11' as provided with a dove-tailed recess 15', and the member H' dove-tailed to correspond. 50 I have also shown the other element 1' as provided on its outer side with two recesses or more properly "channels," one of which as indicated at 5' is semi-circular to admit a round member O', and the other of which 55 as shown at 5'' is angular to admit an angular member O''. It will be clear that the member O might have a quite wide slot 16 so that it is in effect forked, and the parts O' and O'' in Fig. 6 could be fork-arms. 60 Also, without further illustration, it will be clear that this member might be in two parts entirely separate from each other, and if they laid in the separate grooves or channels 5' and 5'' they would be clamped to 65 the hinge element 1' when the nut on the

bolt is set up tight. For this purpose a large washer 24 may be necessary as seen in this view. I have also made use of Fig. 6 to show how the device might become a friction lock hinge instead of a positive lock 70 hinge as doubtless the construction in Fig. 3 would produce. That is to say, a spring 25 is threaded over the tip of the bolt 20 after it is run through the various holes herein shown, and this spring stands beneath the nut 23—with or without washers at either end of it as desired. When now this nut is set up tight, all parts shown separated in this view are drawn into close contact with each other, but the force which holds them in such contact is a yielding one by reason of the presence of the spring 25. When therefore it is desired to adjust the members and the washers axially around the pintle, all that is necessary is to grasp the 80 members H and O and turn them with sufficient force to overcome the tension of the spring. If this is not easy, the nut may be loosened a trifle and then reset after adjustment.

Thus it will be seen that my lock hinge is in effect composed of a pair of washers peculiarly constructed so that their adjacent faces make engagement with each other when they are brought into contact and their outer faces make engagement with the members which it is desired to connect. The uses of such a device are many, and as first above explained I do not wish to be confined to such use upon a scaffold bracket only. 90 Also as above intimated, the protuberances and depressions could take any shape which will set up friction between the contiguous faces of the washers, and they could be reduced in size to such an extent that this friction becomes very little; in fact, they could be done away with entirely if the nut be set up sufficiently tight.

What I claim is:

1. A hinge for connecting two members comprising two washers having their inner faces in contact and their outer faces provided with transverse channels of a size to loosely receive said members, and a bolt extending through said washers and their channels with its head outside one member and its nut outside the other.

2. A hinge for connecting two longitudinally slotted members comprising two washers having their inner faces in contact and their outer faces provided with transverse channels extending diametrically across the washer-holes and of a size to loosely receive said members, and a bolt extending through said holes in the washers and slots in the members, for the purpose set forth.

3. A hinge for connecting two members comprising two washers having their inner faces roughened and in frictional contact and their outer faces transversely channeled

to loosely receive the respective members, and means for clamping the members in the channels and for increasing the friction between said roughened faces.

5 4. A lock hinge comprising two washers having their outer faces channeled to engage the members which are to be connected, a pintle pivotally uniting said washers, and clamping means on the pintle for simultaneously holding said members in engagement with the channels and bearing said washers into frictional contact with each other.

15 5. A friction lock hinge comprising a bolt and its nut, a spring on the bolt, and two washers also on the bolt having their inner faces roughened and adapted to make contact with each other and their outer faces channeled and adapted to adjustably receive the members which are to be connected, the setting up of the nut putting said spring under tension and clamping all parts frictionally in their adjusted positions.

20 6. A hinge for connecting members, comprising washers having their contiguous faces in contact and each provided with an opening whose length is at right angles to the axis of the washer-hole and whose size is such that it will adjustably receive its member, and unitary means for clamping the members in their respective openings and pivotally connecting the washers.

25 7. A hinge for connecting members which are to swing in parallel planes, the same comprising washers having their adjacent faces in contact and each provided with an opening intersecting the washer-hole and of a size to receive its member, a pintle extending through all said holes and across

all said openings, and unitary means for 40 clamping the members to their washers and the washers together.

8. A hinge for connecting members which are provided with openings, the same comprising elements disposed between said members with their contiguous faces in contact and their bodies provided with alined holes opposite the openings in the members, a pintle extending through said holes to pivotally connect the elements and extending also 50 through said openings to adjustably connect the members with their adjacent elements, and binding means on the pintle for holding all parts together.

9. The herein described connection for 55 two members, the same comprising a plurality of washers disposed between said members and with their holes alined, a bolt extending through said holes to pivotally connect the washers, and means on the same 60 bolt for holding each member upon its contiguous washer and permitting its adjustment thereover.

10. The herein described connection for 65 two members, the same comprising two contacting washers disposed between said members with their holes alined, a pintle extending through said holes, and means engaging the ends of the pintle for permitting the adjustment of the members over their respective washers and for clamping all parts together.

In testimony whereof I affix my signature in presence of two witnesses.
